UNITED STATES PATENT OFFICE.

JOHN F. HAVEMEYER, OF ARDSLEY-ON-HUDSON, NEW YORK.

TIE-PIECE FOR METALLIC REINFORCES.

1,296,513.

Specification of Letters Patent. Patented Mar. 4, 1919.

Application filed November 12, 1913, Serial No. 800,470. Renewed February 14, 1918. Serial No. 217,253.

To all whom it may concern:

Be it known that I, JOHN F. HAVEMEYER, a citizen of the United States of America, and a resident of Ardsley-on-Hudson, county 5 of Westchester, State of New York, have invented an Improvement in Tie-Pieces for Metallic Reinforces, of which the following description, in connection with the accompanying drawings, is a specification, like letters on the drawings representing like parts.

This invention relates to improvements in ties or clips for use in connection with the reinforcing bars of concrete structures and has for its objects the provision of means to hold the reinforcing bars or rods together at their crossing points and also the provision of means for supporting these bars above the centering so that they may be most effectively positioned in the composite structure.

Heretofore, ties or clips of this general class have generally been so made that in attaching them it is necessary to pass the device under the reinforcing rods. By means of the construction here shown it is possible to attach the clip from above, thus greatly facilitating the work of placing and arranging reinforcing bars.

The character of this invention will be readily understood by referring to the accompanying drawings in which:

Figure 1 is a plan view of one embodiment of the invention;

Fig. 2 is an elevation of the form shown in Fig. 1 as it would appear attached to the reinforcing bars and embedded in the concrete structure;

Fig. 3 is a plan view of another embodiment of the invention;

Fig. 4 is an elevation of the form shown in Fig. 3 as it would appear in use, and

Fig. 5 is a perspective view of the form shown in Fig. 3.

Referring to the drawings, Figs. 1 and 2 show an embodiment of this invention which is more particularly adapted for use with heavy reinforces. The embodiment shown in Figs. 3 and 5 is adapted for use with comparatively light reinforces. Referring again to Fig. 1 it will be seen that the clip 50 is made of a single length of moderately heavy spring wire which is, by suitable means, bent into the form and shape here shown. The tie or clip in this extended position consists of two substantially parallel runs *a* and *b*. These runs are bent back sharply at points indicated by *c*, *d*, *e*, and *f*.

The runs *a* and *b* are adapted to be bent over the upper or longitudinal bar to form a yoke or yokes engaging said bar at or near its place of intersection with the lower or transverse bar in such manner that the points *c*, *d*, *e*, and *f* will extend below the transverse bar and rest upon the centering *s*. For engagement with the lower or transverse bar loops *g* and *h* are formed by upwardly extending portions *i*, *j*, *k*, and *l* of the tie. These loops are provided with shoulders *m*, *n*, *o*, and *p* for engagement with the lower surface of the transverse bar.

The form of the shoulders may be varied to suit varying conditions of use. Two forms are shown in the drawings. In Fig. 1 one of the shoulders on each loop, namely shoulders *m* and *o* are so made as to overlap the corresponding shoulders *n* and *p* and are adapted to pass completely under the lower bar, thus providing firm and positive supports. This form is more particularly adapted for use with heavy bars. The embodiment of this invention shown in Figs. 3 and 5 is more particularly adapted for use with light reinforces and in this form the shoulders do not overlap. The spring pressure holding these shoulders together will be ample to prevent the lower rods from slipping out when the clip or tie is thus used. This form of tie can be attached more easily and quickly than the form shown in Figs. 1 and 2.

Figs. 2, 4 and 5 show the device as it will appear in use. A reinforcing bar *q* is shown resting upon and supported by another bar *r*. In Fig. 2 the bar *r* is in turn supported mainly by the shoulders *m* and *o* (the shoulder *o* being hidden in this figure). Fig. 5 illustrates the mode of application of the second alternative form of tie, that shown by Fig. 1, and here the four shoulders *m*, *n*, *o*, and *p* all coöperate to support the lower bar. In both cases the loops or yokes *a* and *b* pass over the upper bar *q* and hold it in firm engagement with the lower bar *r*. Fig. 4 illustrates the adaptability of the device to different sized rods. The device is so constructed that the loops *a* and *b* will tend to spring apart as indicated by the dotted lines in Fig. 4, thus bringing the shoulders *m*, *n*, *o* and *p* into close engagement with the lower bar.

As indicated above a great advantage which this tie possesses over others of this general character is the facility with which

it may be attached to the reinforcing rods. To apply the clip after rods have been laid in position upon the temporary molds or centerings the workman grasps the lower rod 5 and lifts it slightly. One of the lower loops of the tie, loop *h* for instance, may then be snapped over this lower rod. The loops or runs *a* and *b* are then bent over the top rod and the other lower loop *g* is snapped 10 over the first named rod on the opposite side of the point of intersection. The spring pressure in the yokes *a* and *b* tends to raise the lower loops *g* and *h* and to press the shoulders *m*, *n*, *o* and *p* firmly against the 15 lower rod. The spring pressure in the loops *g* and *h* keeps these loops from spreading and releasing the lower bar. The workman then releases his hold upon the lower rod and the rods, firmly held together are supported 20 above the centering by the feet, *c*, *d*, *e* and *f*.

It will be clear that the improved tie-piece may be produced otherwise than from wire, the latter being used in the present case simply to illustrate and explain the invention. 25 The outline of Fig. 3, for instance, may be regarded as indicating the edges of a strip of resilient metal which would be substantially as effective in carrying out the improvements as is the wire. Thus, in its broadest aspect, the invention consists of a resilient yoke (illustrated in the present case by the two loops which pass over the top bar) each side member of which is divided so as to 30 form a resilient collar which is sprung around so as to engage and hold the lower rod; and the dividing of the side members of the yoke serves to form four legs, so to speak, upon which the device as a whole is 35 supported upon the centering. And as before called to attention, the yoke being resilient, the side members preferably tend to 40 spread apart so as to hold the rods together.

I claim as my invention:—

- 45 1. A tie-piece for intersecting rods in concrete construction, comprising a resilient yoke adapted to embrace one of the rods, each side member of the yoke being divided into two separate parts, thereby providing 50 means to fit over, embrace and hold the other rod.

2. A tie-piece for intersecting rods in concrete construction, comprising a resilient

yoke adapted to embrace the upper rod, each side member of the yoke being divided into 55 two separate parts to form a loop and two independent legs in order to receive the lower rod and to support the rods above the centering.

3. A tie-piece for intersecting rods in concrete construction, comprising resilient yokes adapted to embrace the upper rod, loops formed between said yokes for engagement with the lower rod, said loops lying in planes at right angles to the planes of said 65 yokes, and downwardly extending projections between each yoke and loop, whereby the rods are held together and supported above the centering.

4. A combined clip and support for metallic reinforces, comprising a pair of loops to engage and support one of two intersecting rods, a pair of yokes yieldingly united to the pair of loops to pass over the other rod, and supports formed by projections 70 between the said loops and yokes, whereby the rods are held in close engagement with each other and are supported above the centering.

5. A combined clip and support for securing and supporting metallic reinforces at their points of intersection, comprising two pairs of wire loops, one pair adapted to engage and support the lower rod, the other pair to engage and pass over the upper rod, 80 said first named pair of loops lying in planes at right angles to the planes of said second pair of loops, and supports formed by the wire between the several loops.

6. A combined clip and support for metallic reinforces, comprising a pair of wire yokes adapted to pass over and engage one of two intersecting rods, said yokes being extended downwardly to form supports for the rods, and a pair of loops integral with 90 the yokes passing around the other rod, whereby the rods are firmly held together and supported above the centering.

In testimony whereof, I have signed my name to this specification, in the presence of 100 two subscribing witnesses.

JOHN F. HAVEMEYER.
